UNITED STATES PATENT OFFICE

2,585,263

KITE STRING REEL

Franklin S. Miller, Elmwood Park, Ill.

Application June 29, 1946, Serial No. 680,462

1 Claim. (Cl. 242—101)

1

My invention relates to kite string winding, and feeding out or reeling devices.

An important object of my invention is to provide a box-like structure in which a central square mandril or spindle is secured having four winding blade elements secured thereto, so that adjacent winding elements, and the string wound thereupon form triangulated space areas. The said central spindle or axle being provided with winding means to permit the string to be wound up, or to be payed out; the one wall of the case of my invention being provided with a hardened, or porcelain guide means to prevent wear of the kite string being payed out, or reeled in.

Another object of my invention is to provide a device of the afore-mentioned character, which is simple in construction, easy to manipulate, practical and efficient for the purposes for which it is destined to be used, and of such simple elemental construction as to warrant economical manufacture thereof in quantity production.

Other features, and ancillary objects, inherent in my invention will become apparent from an examination of the accompanying drawings, bearing further elucidation in the ensuing description, wherein like symbols are used to designate like parts, and in which;

Fig. 1 is a perspective view of my invention.

Fig. 2 is a top view, with certain portions in section and broken away, in order to more clearly exhibit and depict the elemental structure of my invention.

Fig. 3 is an end view of the reeling structure used in connection with my invention.

Fig. 4 is the guide means, secured to one wall of my invention, to prevent wear of the string being payed out, or reeled in.

Referring to the various views, my invention is generally designated 5, and consists of four walls 6, preferably resolving an elongated box-like formation, open at the top and bottom, and being provided with bored openings on two opposed walls, preferably the long walls, in order to accommodate the trunnions 8 of the square central reel spindle 7, which is of square formation, in order to have secured thereto the reel slats, or blades, or elements, 16, 17, 18 and 19, which in turn are provided with arcuate end portions, respectively, designated 20, 21, 22 and 23 on which the string 24 is wound, as indicated in Fig. 1 and Fig. 3.

The central spindle 7 is provided with a central bore 9 in which is secured by drive fit the axle 10, having the shoulder 14 for receiving thereagainst the handle lever 11, secured rigidly in place by the nut 12 and the washer 13. The handle 15 may be

2

rigidly connected, or swivelled to the other terminal of the handle lever 11.

The winding of the string 24 of the reel causes a series of triangular cored spaces, designated 27 each being formed between adjacent slats, or blades, for example, those designated 16 and 17, so that four such spaces are formed, thus the thread will wind up neatly, and be free from any dirt or foreign substance, which will be prevented from accumulating on the reel structure itself, in view of the fact that it is the province of the guide and stripper bushing 25 to so function. The bushing 25 is firmly lodged in the front wall of the box-like structure 6, where the end 15 of the string 26 leading to the kite is either payed out, or wound up by the operation of rotating the handle element 15, or by releasing the same and using the hand to brake the velocity of unwinding of the reel structure in the center thereof.

20 The use of the device is obvious and self-evident as indicated in Fig. 1. The device is very economical to manufacture, and certain simplifications may be resorted to, that is, if preferable, looking at Fig. 2 one trunnion 8 may be extended, and one end of the lever 11 suitably bored, may be fitted thereonto by a drive fit; while the handle 15 may be driven into the other end of the lever 11 without using the pivotal studs shown.

I believed I have herein described, rather succinctly, the construction, use and operation of my invention, and inasmuch as the same is susceptible of modifications, alterations, and improvements, I hereby reserve the right to all modifications, alterations, and improvements, 35 coming within the scope and spirit of my invention and disclosure, as well as any that are suggestively indicated and depicted in the accompanying drawings, as well as any that may fall within the purview of the foregoing description and disclosure; my invention to be limited only to the subjoined claim.

Having thus described and revealed my invention, what I claim as novel, and desire to secure by Letters Patent, is:

45 A kite string reel, comprising a four walled box structure, a square spindle provided with cylindrical trunnions journaled between opposite walls of the said box, string winder blades of rectangular formation and rigid construction fixedly secured each to a face on the said square spindle in transversal relationship therewith whereby one end of any blade is perpendicular to and in contact with an adjacent blade at a point intermediate the ends of said adjacent blade, the said 50 winder blades being provided with arcuately

formed recesses on their free edges adapted to retain a quantity of kite string and permit reeling up and paying out the same, handle means rigidly secured to one end of the said spindle, and obliquely positioned bushing means adapted to feed therethrough the kite string, the said bushing being secured to one of the remaining walls.

FRANKLIN S. MILLER.
